UNITED STATES PATENT OFFICE.

ALFRED J. HEYER, OF ST. LOUIS, MISSOURI, ASSIGNOR TO HARRY L. HUSSMANN
REFRIGERATOR & SUPPLY COMPANY, OF ST. LOUIS, MISSOURI, A CORPORATION
OF MISSOURI.

DESIGN FOR A REFRIGERATOR HINGE.

Application filed November 25, 1922. Serial No. 4,398. Term of patent 3½ years.

To all whom it may concern:

Be it known that I, ALFRED J. HEYER, a citizen of the United States, residing at St. Louis, Missouri, have invented a new, original, and ornamental Design for Refrigerator Hinge, of which the following is a specification, reference being had to the accompanying drawing, forming part thereof.

The figure represents a perspective view of a hinge showing the new design.

I claim:

The ornamental design for a refrigerator hinge, as shown.

In testimony whereof I have hereunto affixed my signature this 6th day of July, 1922.

ALFRED J. HEYER.
